UNITED STATES PATENT OFFICE.

HENRIETTA M. STRUBLE, OF GENESEO, NEW YORK.

MANICURING INSTRUMENT.

1,289,952.

Specification of Letters Patent. Patented Dec. 31, 1918.

Application filed July 10, 1917. Serial No. 179,728.

To all whom it may concern:

Be it known that I, HENRIETTA M. STRUBLE, a citizen of the United States, residing at Geneseo, in the county of Livingston and 5 State of New York, have invented new and useful Improvements in Manicuring Instruments, of which the following is a specification.

This invention relates to manicuring instruments.

The primary object of the invention is to provide a simple, cheap and neat device, which may be conveniently held for movement over the finger and toe nails, for the 15 purpose of loosening the cuticle, in order to remove the same and to treat the nails in the well known manner.

For the accomplishment of this purpose the invention comprises a transversely curved relatively wide body member, shaped to comfortably fit the inner side of the fingers to provide a convenient handle and a transversely curved reduced operating end, said end being curved in a manner to provide 25 a bevel for engagement with the surface of the finger or toe nails when the instrument is held at an angle thereto.

In the drawings,

Figure 1 illustrates the instrument and the 30 manner of using the same, that portion of the instrument which lies below the hand being shown by dotted lines;

Fig. 2 is a detailed perspective view of the instrument;

Fig. 3 is a transverse sectional view 35 through the reduced operating end; and

Fig. 4 is a similar view through the curved body member.

Referring to the drawings in detail, the 40 reference character 10 indicates the body portion of the instrument, which is transversely curved as shown, the curvature being such that the said body portion will conveniently fit the inside of the fingers and 45 permit the thumb to rest within the curved portion, when the instrument is held in position for use. The end 11 may also be curved as desired.

The instrument is also formed with a transversely curved reduced operating end 50 12, which is formed with a curved nail contact in the end 13, the curvature of this end being such as to provide a bevel, which, when the instrument is held at an angle to the nail, the said curved or beveled end 13 55 will contact with the surface of the said nail. This provides a convenient means for keeping the instrument at the proper angle when moved over the surface of the nail for engagement with the cuticle, the angle at 60 which the instrument is held being most advantageous for the loosening of the cuticle, the transverse curvature of the operating end being such as to most conveniently conform to the curvature of the flesh 65 surrounding the nail. It has been found by practice that the curvature of the portions 12 and 13, if made to conform to the shape of the inner ends of an ordinary penpoint is capable of best results.

It is believed that from the foregoing description when taken in connection with the accompanying drawings, the construction and advantages of the invention will be apparent and that a more extended description is unnecessary.

Having described the invention, what is claimed is:

A device of the character described formed from a single sheet of material and comprising the handle portion formed concavo-convex throughout its length, one end of said handle portion being curved more abruptly than the remainder thereof to provide a relatively narrow operating end, the 80 extremity of said operating end being curved for conforming engagement with the cuticle at the base of a nail, the transverse curvature of said operating end being conformingly similar to the curvature of a nail, and 85 the concave side of said handle being adapted for engagement by the operator's thumb whereby twisting of said handle between the fingers will be prevented.

In testimony whereof I affix my signature. 95
HENRIETTA M. STRUBLE.
